Primary Examiner—Philip S. Hyder*Assistant Examiner*—RoseLynne (Ulm) Cody(74) Attorney, Agent, or Firm—William W. Cochran; Cochran Freund & Young LLC(57) CLAIM

The ornamental design for a laptop case, as shown and described.

DESCRIPTION

FIG. 1 is an isometric view of a laptop case showing my new design.

FIG. 2 is a front view thereof.

FIG. 3 is a top view thereof.

FIG. 4 is a left side view thereof.

FIG. 5 is a right side view thereof.

FIG. 6 is a rear side view thereof; and,

FIG. 7 is a bottom view thereof.

The broken line portions of the disclosure are for illustrative purposes only and form no part of the claimed design.
